AWNING

Isidore P. Smith, Perrysburg, Ohio, assignor to
The Hettrick Manufacturing Company, Toledo,
Ohio, a corporation of Ohio

Application June 16, 1937, Serial No. 148,440

3 Claims. (Cl. 156—15)

This invention relates to awnings and an object is to produce a new and improved mounting for the upper portion of an awning which is so constructed and arranged that the awning can be readily and conveniently attached or removed and when in place lies in close juxtaposition to the building, the arrangement being such that it can be inexpensively manufactured on a production basis.

10 Other objects and advantages of the invention will hereinafter appear and an embodiment of the invention is shown by way of illustration on the accompanying drawing in which

Figure 1 is a perspective view of an awning mounted in position of use showing particularly the means for holding the upper end portion of the awning in position;

15 Fig. 2 is an enlarged detailed fragmentary view of an upper corner portion of the awning showing the means for mounting it;

20 Fig. 3 is a transverse sectional view on the line 3—3 of Fig. 2;

Fig. 4 is a sectional view on the line 4—4 of Fig. 2;

25 Fig. 5 is a longitudinal sectional view on the line 5—5 of Fig. 2; and

Fig. 6 is a fragmentary view of the upper portion of the awning showing the inner side thereof.

30 The illustrated embodiment of the invention comprises an awning having a downwardly and outwardly inclined fabric portion 10 to which side wings 11 are suitably secured and having the usual scalloped edge portion 12. The awning is shown mounted on the side of a wall 13, the lower end being held in place by a U-shaped metal frame member 14 suitably disposed in a pocket in the lower portion of the awning and held to the wall 13 by any suitable fastening

40 device 15.

Heretofore, difficulty has been experienced in mounting the upper end portion of the awning. Clamps have been employed but these are not only difficult to manipulate for properly engaging the awning structure but also militate against positioning the awning in sufficiently close juxtaposition to the wall or building to which the awning is attached. Other fastening devices have proven either too expensive from a manufacturing standpoint or are so inconvenient to install that their usefulness is of doubtful value. This invention overcomes the difficulties and troubles heretofore experienced and provides an exceedingly satisfactory mounting which can be readily and conveniently installed and which can

be inexpensively manufactured on a large scale production.

As indicated in Figure 6, the upper end of the fabric portion 10 is folded downwardly upon itself with the free edge turned under and secured in place by a line of stitching 16 to provide a pocket 17 which extends horizontally of the upper end of the awning, the extreme outer end portions of the pocket being secured together by lines of stitching 18. An opening is cut in the 10 overlapped portions at each end portion of the overlap to receive a brass grommet 19 having a horizontally elongate opening 20. It will be seen that the grommet which is clamped on in the usual fashion engages two thicknesses of the 15 material and since awnings are ordinarily made of canvas, adequate reinforcing is provided. Spaced a short distance inwardly from the edge of each grommet 20 a slit 21 is formed in the inner ply of the overlapped material and disposed in the pocket 17 by inserting the same through one of the openings provided by the slits 21 is a header bar 22 which is of metal and is flat on the opposite sides. The length of the header bar 22 is sufficient so that the end portions 25 project beyond the mountings provided by the slits 21 so as to be disposed directly in rear of the elongate openings 20 of the grommets 19. Formed in each end portion of the header bar 22 is a horizontally elongate opening 23 which is 30 adapted to register with the openings 20 of the grommets 19.

It will be apparent that the upper end portion of the awning can lie flatly against the wall or building structure 13 and is held in place by a 35 screw 24 having a head 25 of such size as to pass through the registering openings 20 and 23 and then the head can be turned at right angles to the openings as indicated in Figure 3 for holding the awning in position. In this instance, the head 40 25 is rounded so that a certain camming action is provided in tightening the awning in position. Obviously the fastening screws 24 can be readily mounted in position and by a slight turning movement thereof can be disposed so that the 45 awning can be mounted in place. Thereafter, the heads 25 are turned to such position as to hold the awning in position. As shown in Figure 6, the side wings 11 may enter between the overlapped portions and thereby afford additional reinforcing in the region of the grommets 19.

It is to be understood that numerous changes in details of construction, arrangement and operation may be effected without departing from 55

the spirit of the invention especially as defined in the appended claims.

What I claim is:

- 5 1. In an awning having a downwardly and outwardly inclined fabric portion, means to hold the lower end of the fabric portion in the desired position, means providing a horizontal pocket in the upper portion of said fabric portion, said pocket terminating at its opposite ends short of the side edges of the fabric portion, a horizontally elongate grommet in the fabric portion between each side edge thereof and the adjacent end of said pocket, a removable header bar in said pocket having end portions projecting beyond the ends thereof and disposed in rear of said grommets, said bar having horizontally elongate openings substantially registering with said grommets respectively, and a headed fastener extending through each pair of bar and grommet openings respectively, thereby to support the upper end portion of the awning, and to prevent relative sliding movement between the header bar and the pocketed upper portion of the fabric portion.
- 10 2. In an awning having a downwardly and outwardly inclined fabric portion, means to hold the lower end of the fabric portion in the desired position, means providing a horizontal pocket in the upper portion of said fabric portion, said pocket terminating at the opposite ends short of the side edges of the fabric portion, a horizontally elongated grommet in the fabric portion between

each side edge thereof and the adjacent end of said pocket, a removable flat metallic header bar in said pocket having end portions projecting beyond the ends of said pocket and disposed in rear of said grommets, said bar having horizontally elongate openings substantially registering with said grommets respectively, and a headed fastener extending through each pair of bar and grommet openings respectively, thereby to support the upper end portion of the awning 10 and header bar and enable the same to be disengaged from the fastener by turning the latter to pass through the registering openings.

3. In an awning of the character described, having its upper edge formed to provide a transversely extending pocket having front and rear walls, a grommet member adjacent each of the ends of the pocket and extending through said front and rear walls thereof to provide an opening therethrough, said pocket having a vertically 20 extending slit formed in the rear wall thereof adjacent the inner edges of said grommet openings so as to provide means of ingress to and egress from said pocket, a header bar disposed in the pocket and having projecting end portions 25 formed with openings adapted to register with the grommet openings, and supporting means for the awning having parts extending through the openings in the header bar and pocket, whereby to prevent relative sliding movement 30 between the awning and header bar.

ISIDORE P. SMITH.
